UNITED STATES PATENT OFFICE.

JULES EMILE HENRI BÉRAUD, OF ASNIÈRES, FRANCE.

TIME-SWITCH.

1,123,072.

Specification of Letters Patent.

Patented Dec. 29, 1914.

Application filed January 3, 1914. Serial No. 810,138.

To all whom it may concern:

Be it known that I, JULES EMILE HENRI BÉRAUD, a citizen of the Republic of France, and a resident of 34 Rue Bapst, Asnières, Seine, France, have invented a new and useful Time-Switch, of which the following is a specification.

This invention relates to time switches which can be operated directly by hand for the purpose of effecting during a determined period of time, the lighting up of electric lamps.

The object of the invention is to produce an apparatus of this kind which is particularly simple and which contains neither a clockwork movement nor an electromagnet.

The apparatus is composed broadly of two vessels which communicate with each other and contain a certain quantity of mercury and in one of which slides with slight friction an air bell which is not packed. By pressing upon a button, the bell is raised and filled with air after which it sinks down into the mercury so that the level thereof rises in the other communicating vessel which causes the closing of the circuit. The air then escapes slowly from the bell, the mercury resumes, at the end of a fixed period of time, its original level and the current is switched off again.

A constructional form of the subject matter of the invention is represented by way of example in the accompanying drawing which shows in—

Figure 1 an elevation, partially in section, of the apparatus. Fig. 2 a plan view partially in section. Fig. 3 a section on the line 5—5 of Fig. 1. Fig. 4 on a larger scale a section of the air bell on the line 4—4 of Fig. 2. Fig. 5 is a section, likewise on a larger scale, on the line 5—5 of Fig. 1.

Upon a projection a on a porcelain base a^1 are mounted two glass cylinders b and c communicating with each other by a furrow a^2 cut in the projection a . These cylinders which form communicating vessels, are filled with mercury up to the level $x-y$. In the tube b , the diameter of which is greater than that of the tube c , slides with slight friction a bell d formed of a glass tube closed at its upper part by a cover d^1 . This cover d^1 of the bell d is pierced by a hole d^2 and is lined internally with a lining e of a porous material such as plaster for example (see particularly Fig. 4) which is capable of allowing the air to filter slowly.

Upon the cover d^1 of the bell d is fixed also a bent arm g g^1 which is acted upon by a spring h which tends to constantly thrust the bell d downward. The end g^1 of the bent arm g g^1 rests upon the lower part of an inclined plane i with which the rod i^1 of a push button i^2 is provided. A roller i^3 facilitates the movement of the rod g^1 .

In the tube c is adapted to slide with slight friction a glass tube m which forms a float. In the axis of the tube m is mounted a conducting rod m^1 , connected by one end to a contact piece m^2 which closes up the upper part of the tube m and held in place at its other end by a plug of plaster m^3 which only partially closes up the lower part of the tube m . The plug m^3 is provided with two perforations m^4 (see particularly Fig. 5) which allow the mercury to pass into the interior of the float m . Above the contact piece m^2 is arranged a similar contact piece o mounted on a knuckle joint on the end of a screw rod o^1 . This rod o^1 is screwed into a conducting support o^2 connected to one of the poles of the current. The other pole of the current is connected by a rod l with the mercury which fills the furrow a^2 .

The working of the apparatus is as follows:—When the bush button i^2 is pressed, the inclined plane i raises the bent lever g g^1 and consequently the bell d which emerges from the mercury and becomes filled with air. When the push button i^1 is released the spring h thrusts down the lever g g^1 and the bell d which sinks into the mercury. The level of the mercury now rises in the tube c and lifts the float m . The contact piece m^2 then comes in contact with the piece o and the excess of mercury rises into the interior of the tube m by passing through the openings m^4 . The current passes through the following circuit viz. the rod l , furrow a^2 , rod m^1 , contact piece m^2 , contact piece o and the lamps in the circuit light up. The air then escapes slowly through the layer of porous material e and through the hole d^2 in the cover d^1 of the bell d , the level of the mercury rises little by little in the tube b and sinks in the tube c , so that at the end of a fixed period of time, the float m drops again under the influence of its own weight and breaks the contact m^2 o . At this moment the mercury is still in contact with the rod m^1 . The breaking of the contact does not affect the

mercury which runs no risk of being changed. The making and breaking of the contact $m^2 o$ is effected in a perfect manner in consequence of the knuckle joint mounting of the contact piece o .

The time during which the current passes may be regulated either by acting upon the screw threaded rod e^1 , or by giving a greater or lesser thickness to the layer of porous material.

It is obvious that the invention is not limited to the constructional form which has just been described above by way of example only.

15 What I claim and desire to secure by Letters Patent of the United States is:—

1. In a time switch, two communicating vessels containing mercury, an air bell floating in one of said vessels, means for momentarily lifting said bell to admit air therein, means for permitting the gradual escape of air therefrom when in floating position, a floating contact in the other vessel and a coöperating contact temporarily engaged thereby on the displacement of the mercury in said vessel consequent upon the admission of air to the air bell in the communicating chamber, substantially as described.

30 2. In a time switch, two communicating vessels containing mercury, an air bell apertured in its upper portion and floating in one of said vessels, a porous closure for said aperture through which the air in said bell 35 may be gradually discharged, a floating contact in the other vessel and a coöperating contact temporarily engaged thereby on the displacement of the mercury in said vessel consequent upon the admission of air to the 40 air bell in the communicating chamber, substantially as described.

3. In a time switch, two communicating vessels containing mercury, an air bell floating in one of said vessels, means for momentarily lifting said bell to admit air therein, means for permitting the gradual escape of air therefrom when in floating position, and means temporarily closing a circuit through the mercury on the displacement of the latter in the other vessel consequent upon the admission of air to the 50 said air bell in the communicating vessel, substantially as described.

4. In a time switch, two communicating vessels containing mercury, an air bell floating in one of said vessels, means for momentarily lifting said bell to admit air therein, means for permitting the gradual escape of air therefrom when in floating

position, a float contact in the second vessel, a coöperating contact engaged thereby on the displacement of the mercury in said second vessel by the air bell in the communicating vessel, said float having passages to permit the rise of mercury therein after said floating contact has engaged the coöperating contact, substantially as described.

5. In a time switch, two communicating vessels containing mercury, an air bell floating in one of said vessels, means for momentarily lifting said bell to admit air therein, means for permitting the gradual escape of air therefrom when in floating position, a float contact in the second vessel, a coöperating contact engaged thereby on the displacement of the mercury in said second vessel by the air bell in the communicating vessel, said coöperating contact comprising a pivoted contact piece adapted to conform to the position of the float contact, substantially as described.

6. In a time switch, two communicating vessels containing mercury, an air bell floating in one of said vessels, means for momentarily lifting said bell to admit air therein, means for permitting the gradual escape of air therefrom when in floating position, a float contact in the second vessel, a coöperating contact engaged thereby on the displacement of the mercury in said second vessel by the air bell in the communicating vessel, said coöperating contact comprising an adjustable screw rod and a contact piece ball-jointed to one end thereof, for the purpose described.

7. In a time switch, two communicating vessels containing mercury, an air bell floating in one of said vessels, a push button with cam face operatively engaging said bell to momentarily lift the same to admit air therein, a spring exerting a downward thrust upon said bell, means for permitting the gradual escape of air from said bell when in floating position, a floating contact in the other vessel and a coöperating contact temporarily engaged thereby on the displacement of the mercury in said vessel consequent upon the admission of air to the air bell in the communicating chamber, substantially as described.

In testimony whereof I have signed my name to this specification, in the presence of two subscribing witnesses.

JULES EMILE HENRI BÉRAUD.
